(57) **CLAIM**

The ornamental design for a stand assist handle attachment, as shown and described.

DESCRIPTION

FIG. 1 is a perspective top elevational view of a stand assist handle attachment showing our new design;
FIG. 2 is a front plan view thereof;
FIG. 3 is a back plan view thereof;
FIG. 4 is a right-side plan view thereof;
FIG. 5 is a left-side plan view thereof;
FIG. 6 is a top elevation view thereof;
FIG. 7 is a bottom elevational view thereof; and,
FIG. 8 is the product view having stand assist handle attachment.

The broken lines are included for the purpose of illustrating environmental structure that forms no part of the claimed design.
